UNITED STATES PATENT OFFICE

WILLIAM N. BOOTH, OF DETROIT, MICHIGAN, ASSIGNOR TO KELSEY-HAYES WHEEL CORPORATION, OF DETROIT, MICHIGAN, A CORPORATION OF NEW YORK

RIM SIZING AND PUNCHING MACHINE

Application filed July 1, 1925. Serial No. 40,943.

The invention relates to machines for sizing and punching rims and is designed particularly for use in sizing and punching vehicle wheel rims such as demountable rims and permanent rims or felloes. One of the objects of the invention is to provide a continually operating machine, which is arranged to successively size and punch the rim during one cycle at the end of which the sized and punched rim may be removed and replaced by another rim to be sized and punched. Other objects are to provide a simple arrangement for guiding both the rim sizing blocks and the rim punch; to provide heads which are reciprocable in directions transverse to those of the rim sizing blocks and punch for actuating the same; and to provide revoluble means for reciprocating the heads and thereby actuating the rim sizing blocks and punch. A further object is the provision of means for shrinking a transversely split rim and then shearing its end portions to make the same parallel. With these as well as other objects in view the invention resides in the novel features of construction and combinations and arrangements of parts as more fully hereinafter set forth.

In the drawings:

Figure 1 is an end view, partly broken away, of a rim sizing and punching machine embodying my invention;

Figure 2 is a vertical median section therethrough;

Figure 3 is a cross section on the line 3-3 of Figure 2;

Figures 4, 5 and 6 are cross sections, respectively, on the lines 4-4, 5-5 and 6-6 of Figure 1.

Figure 7 is an enlarged plan view of the structure shown in Figure 5.

As shown in the present instance, the machine is employed to size and punch a demountable rim 1, which is of the transversely split type and is provided with the apertures 2 near its ends for the passage of the rivets for securing the interlocking plates to the ends of the rim, with the apertures 3 for the passage of the valve stem 4 and with the adjacent apertures 4 for the

passage of the rivets for securing the rim driving lug. The machine has the annular series of radially inwardly movable blocks 5 which are engageable with the rim to shrink the same to size and also the radially outwardly movable holders 6 for the punches and the supporting blocks 7 which are diametrically opposite the holders for the punches which form the apertures 2 and 3 in the rim.

Each block 5 is mounted upon the radially movable segmental shaped slide 8 and each punch holder 6 and supporting block 7 slidably engages in the radially extending channel 9 of the slide 8 at the side thereof. The slides 8 slidably engage in radially extending channels 10 formed in the head 11 of the machine. Any suitable means may be employed for holding the slides 8, blocks 7 and holders 6 in assembled position, herein shown as comprising a pair of rings 7' and 8' secured to the head 11 by means of the bolts 11'.

For actuating the blocks 5 the head 11 is reciprocated in directions transverse to the radial movements of the blocks. As shown, the machine has the annular stationary abutment or frame member 12, which surrounds the slides 8. Intermediate these slides and the stationary abutment or frame member are the toggle links 13, which preferably have their ends journaled upon the pins 14 and 15, respectively, secured to the slides 8 and stationary abutment or frame member 12. The head 11 is secured to the hollow shaft 16, which extends rearwardly and downwardly and is guided by the frame member 17 of the machine. This hollow shaft is reciprocated by means of the cams 18, which are engageable with the rollers 19 preferably at opposite sides of the hollow shaft. The cams 18 are secured upon the crankshaft 20 which is journaled in the base 21 of the machine and is suitably driven by reduction gearing. For holding the rollers 19 against the cams 18 I have provided suitable resilient means such as the coil springs 22 which extend from the head 11 to the lower rear end of the frame member 17.

For actuating the punch holders 6 and 100

supporting blocks 7 there is the head 23 which is mounted upon the shaft 24 and is adapted to be reciprocated by means of the shoulder 25 upon the shaft and the nut 26 threaded upon the end of the shaft, the arrangement being such that the head 23 has a lost motion connection with the shaft 24 and that the amount of travel of the head 23 relative to the shaft 24 is prevented by means of a longitudinally extending key 24' embedded in the shaft 24 and engageable with a longitudinally extending groove formed in the head 23. Suitable toggle links 27 are located between the head 23 and punch holders 6 and supporting blocks 7, these toggle links having their ends journaled upon the pins 28 and 29, which are respectively secured to the punch holders 20 and supporting blocks and the head. The shaft 24 extends concentrically through the head 11 and preferably slidably engages suitable bushings on the hollow shaft 16. This shaft also extends through the hollow shaft 16 and is reciprocated by the crank shaft 20 through the link 30 which pivotally connects the crank shaft to the shaft and is located between the cams 18.

With the arrangement as thus far set forth, it will be seen that my machine may be continuously operated to move the rim sizing blocks and punches, and supporting blocks in timed relation to each other to successively size the rim and punch the same. It will also be seen that a sufficient time interval may be allowed at the end of each cycle to remove the sized punched rim and replace the same with another to be sized and punched.

For the purpose of sizing the transversely split rim and providing ends which are parallel to each other, the punch holder 6 for holding the members 31 which pierce the apertures 2 also holds the combined positioning and shearing member 32 which is located between the piercing members 31. This combined positioning and shearing member has the outer reduced pilot portion 33 which is normally located between the ends of the rim before its end portions are sheared. This member also has the radially inwardly positioned enlarged portion 34 providing the parallel shearing shoulders 35 which are brought into engagement with the end portions of the rim, after the latter has been shrunk to size, to shear these end portions and thereby make the ends of the completed rim parallel to each other, allowance having been made for the stock removed from the rim so that the final dimensions of the rim are correct. The piercing members 31 are located relative to the shearing shoulders 35 so that they come into engagement at practically the same time as the shearing shoulders. The block 5 radially

outward from the punch holder 6 for the combined positioning and shearing member and piercing member also functions to hold the die 36 for cooperating with these members.

The blocks 5 radially outward from the holders for the members 37 and 38 which pierce the apertures 3 and 4, respectively, in the rim, also hold suitable dies 39 and 40 respectively, for cooperating with their respective piercing members.

The supporting blocks 7 are so arranged that they come into contact with the inner face of the rim diametrically opposite the combined positioning and shearing member 32 and piercing members 31 and the piercing member 37 at the time these members are operating upon the rim, thereby holding the rim to size.

The parts are so arranged that the blocks 5 are first moved radially inward to shrink the rim to size and force its ends against the pilot portion 33 of the combined rim end positioning and shearing member 32. Then the punch holders 6 and supporting blocks 7 are moved radially outward to shear the end portions of the rim and pierce the apertures 2, 3 and 4 therein, this occurring while the blocks 5 are being held stationary by reason of the dwells 41 upon the cams 18.

What I claim as my invention is:

1. In a rim sizing and punching machine, the combination with radially inwardly movable blocks engageable with the rim to size the same, of a radially movable punch engageable with the rim and means for actuating said blocks and punch in timed relation to successively size and punch the rim, including heads reciprocable in directions transverse to those of said blocks and punch.

2. In a rim sizing and punching machine, the combination with radially movable blocks engageable with the rim to size the same, of a radially movable punch engageable with the rim and guided by one of said blocks, a head for guiding said blocks, a second head, means for reciprocating said heads in directions transverse to those of said blocks and punch, and means dependent upon the reciprocation of said heads for radially moving said blocks and punch.

3. In a rim sizing and punching machine, the combination with radially movable blocks engageable with the rim to size the same, of a radially movable punch engageable with the rim, a radially movable holder for said punch guided by one of said blocks, a head provided with means for guiding said blocks, a stationary frame member, a second head, toggle links between said stationary frame member and blocks, a toggle link between said second mentioned head and punch holder and means for reciprocating

ing said heads in timed relation to each other and in directions transverse to those of said blocks and punch holder.

4. In a rim sizing and punching machine, the combination with a reciprocable head, of a reciprocable shaft guided by said head, a second head arranged to be reciprocated by said shaft in a direction parallel to that of said first mentioned head, radially movable blocks slidably mounted upon said first mentioned head and engageable with the rim to size the same, a radially movable punch engageable with the rim and means dependent upon the reciprocation of said heads for actuating said blocks and punch.

5. In a rim sizing and punching machine, the combination with positioning means between the ends of the rim, of radially inwardly movable blocks engageable with the rim to shrink the same and force its ends against said positioning means, radially outwardly movable shearing means for shearing the end portions of the rim and means for actuating said blocks and shearing means in time relation to successively shrink the rim and shear its end portions.

6. In a rim sizing and punching machine, the combination with positioning means engageable between the ends of the rim, of radially inwardly movable blocks engageable with the rim to shrink the same and force its ends against said positioning means, radially outwardly movable shearing and piercing means for respectively shearing the end portions of the rim and piercing the rim and means for actuating said blocks and shearing and piercing means in timed relation to successively shrink the rim, shear the end portions of the rim and pierce the rim.

7. In a rim sizing and punching machine, the combination with a combined rim positioning and shearing member and piercing members on opposite sides thereof and a radially outwardly movable holder therefor, of radially inwardly movable blocks engageable with the rim to shrink the same and force its ends against the positioning portion of said combined positioning and shearing member and means for actuating said blocks and holder in timed relation to successively shrink the rim and force its ends into contact with the positioning portion of said combined positioning and shearing member and shear the end portions of the rim and pierce the rim.

8. In a rim sizing and punching machine, the combination with radially movable blocks engageable with the rim to size the same, of a radially movable punch guided by one of said blocks and engageable with the rim and revolute means for actuating the blocks and punch to bring the same successively into engagement with the rim.

9. In a rim sizing and punching machine,

the combination with radially inwardly movable blocks engageable with the rim to size the same, of a radially outwardly movable punch engageable with the rim, means reciprocable in directions transverse to those of said blocks and punch for actuating the same and revolute means for reciprocating said reciprocable means.

10. In a rim sizing and punching machine, the combination with radially movable blocks engageable with the rim to size the same, of a radially movable punch engageable with the rim and means for actuating said blocks and punch in timed relation to successively size and punch the rim, including heads reciprocable in directions transverse to those of said blocks and punch, a crank shaft connected to one of said heads and a cam for actuating the other of said heads, said cam being rotated by said crank shaft.

11. In a rim sizing and punching machine, the combination with a head, of a member slidably mounted upon said head and capable of radial movement with respect thereto, a sizing block carried by said member and engageable with the rim, a radially movable punch slidably mounted upon said member and engageable with the rim, and means for actuating said rim sizing means and punch in timed relation to successively size and punch the rim.

12. In a rim sizing and punching machine having a frame, the combination with a reciprocable head, of a member slidably mounted upon said head and capable of radial movement with respect thereto, a sizing block carried by said member, a connection between said head and frame for moving the said member radially to engage said block with said rim, a punch slidably mounted upon said member and engageable with the rim, and means dependent upon the reciprocation of said head for actuating said punch.

13. In a rim sizing and punching machine, the combination with radially movable blocks engageable with the rim to size the same, of radially movable shearing and piercing means for respectively shearing the end portions of the rim and piercing the rim, and revolute means for actuating said blocks and shearing and punching means in timed relation to successively shrink the rim, shear the end portions of the rim and pierce the rim.

14. In a rim sizing and punching machine, the combination with a reciprocable head, of radially movable blocks slidably mounted upon said head and engageable with the rim to size the same, a stationary frame, toggle links between said frame and blocks for moving the latter radially upon movement of said head, a punch slidably mounted upon said head and engageable

with the rim, and means for actuating said punch.

15. In a metal working machine, the combination of a head having a first series of 5 jaws thereon arranged in circumferential relation, and a second series of jaws arranged concentrically within the first series of jaws, means including toggle mechanisms operating upon the first series of jaws to cause them to move into engagement with an annular piece of work to shrink it to a pre-determined diameter, and means subsequently operating upon the second series of jaws to move them into engagement with the 10 work, said second series of jaws being adapted to perforate the work.

16. A metal working machine having in combination, a plurality of radially disposed members movable inwardly into engagement with an annular piece of work to size it, a plurality of cutting tools operable upon the work held by said sizing members, and mechanically operating means for operating the sizing members and cutting tools successively including abutment members and 20 toggle links between the abutment members on the one hand and the sizing members and tools on the other hand.

17. A machine of the character described comprising a stationary ring member, a table mounted for axial movement in said ring member, two sets of jaws mounted for radial movement relative to the table, a head arranged coaxially with respect to the table, 30 toggle links between the jaws of one of said sets and said ring member and between the jaws of the other set and said head, and means for effecting relative movement between the table and said ring member on the one hand and between said head and the table on the other hand whereby to move the jaws of the two sets into engagement with opposite sides of the work.

18. A machine of the character described 45 having a stationary ring member, a head movable axially with respect to said ring member and comprising a table, an annular plate mounted on the table in spaced relation thereto, a plurality of slide members 50 slidable between said table and said annular plate so as to be guided thereby, toggle links between each of said slide members and said ring member, another slide member mounted on one of the first mentioned 55 slide members, a second head mounted axially with respect to the table, a toggle link between said second head and said other slide member, and means for moving the table and said second head in opposite directions.

19. A machine of the character described 60 having a stationary ring member, a main head movable axially with respect to said ring member and comprising a table, an annular plate mounted on the table in spaced

relation thereto, a plurality of slide members 70 slidable between said table and said annular plate so as to be guided thereby, toggle links between each of said slide members and said ring member, another slide member mounted on the main head, a second head mounted axially with respect to the table, a toggle link between said second head and said other slide member, and means for moving the table and said second head successively in opposite directions. 75

20. A machine of the character described comprising, in combination, a driven shaft, a table having a plurality of slide members thereon arranged in circular series, a head mounted coaxially with respect to the table, jaws on certain of said slide members, and means operable to move said slide members in one direction and said jaws in the opposite direction comprising a cam on said shaft operatively associated with said table, and a drawbar operatively associated with the shaft and having a lost-motion connection with said head. 80

21. A machine of the character described 85 comprising a head having two sets of jaws mounted thereon for radial sliding movement, and means for operating said jaws in opposite directions including a shaft having cam means operatively associated with the head and a drawbar also operatively associated with said shaft and having a lost-motion connection with the jaws of one of said sets. 90

22. A machine of the character described 95 having two relatively movable axially aligned heads, toggle mechanisms arranged to be actuated in the movements of said heads and cam-actuated means for effecting relative movement between the heads including a shaft having a lost-motion connection with one of said heads. 105

23. A machine of the character described 110 having a pair of heads, cam means for actuating said heads and arranged to operate at a uniform speed, two tool-carrying members operable in the movements of the respective heads, said cam means being adapted to actuate the respective members in succession, and means including a lost-motion connection operable to cause the member first actuated to remain in engagement with the work while the second member is actuated. 115

24. A machine of the character described 120 having a pair of concentrically arranged members mounted for relative axial movement, a pair of jaws radially slidably between said members, toggle mechanisms interposed between the respective jaws and members, and means operating to cause relative axial movement between the members and the jaws to operate said toggle mechanisms. 125

25. In a machine of the character de- 130

scribed, the combination of a pair of heads, a pair of toggle mechanisms arranged to be actuated in the movements of each of said heads respectively, an operating member for each of said heads, and a driven shaft operatively associated with each of said members to actuate them, one of said heads during a portion of its movement acting independently of the other head.

26. In a machine of the character described, the combination of a pair of tool slides and means for actuating said slides comprising a pair of heads, a pair of toggle mechanisms arranged to be actuated in the movements of each of said heads respectively, an operating member for each of said heads, and a driven shaft operatively associated with each of said members to actuate them, the operative association between said operating shaft and the respective heads being such that one of the slides is first moved into holding engagement with the work and the other slide is then moved into engagement with the work while held by the first slide.

27. In a machine of the character described, a pair of tool slides, a pair of members arranged to actuate the respective slides, a driven shaft having an eccentric portion connected with one of said members, and a cam associated with the other one of said members, the arrangement being such that when the cam has caused its corresponding slide to move into operative position relative to the work, said eccentric will cause the other slide to move into operative position also.

28. A machine of the character described comprising a frame, a head mounted in the frame and having a set of radially slidable jaws thereon, another radially slidable jaw within the first set of jaws, means operable to cause the set of jaws to move inwardly, and means operable to cause said other jaw to move outwardly, the last mentioned means comprising a shaft extending through the head coaxially thereof, a toggle mechanism operable between said shaft and said other jaw, and means for transmitting the lateral strain on said shaft to the frame.

29. In a machine of the character described, the combination of a pair of heads and an abutment mounted for relative movement, one of said heads being arranged intermediate said abutment and the other head, a pair of jaws mounted on the intermediate head, and means operating in the relative movement between the heads, and said abutment to move said jaws in opposite directions.

30. In a machine of the character described, the combination of a pair of heads and an abutment mounted for relative axial movement, one of said heads being arranged intermediate the abutment and the other

head, a pair of jaws mounted on the intermediate head, and toggle links respectively coacting with said other head and the abutment on the one hand and with said jaws on the other and operable upon relative movement between the abutment and heads to cause said jaws to move in opposite directions.

31. In a machine of the character described, the combination of a substantially circular table, an annular member stationary supported adjacent the table, a central head arranged concentrically within the stationary member in spaced relation thereto, a slide on the table having a pair of jaws interposed between said member and the head, toggle links interposed between the respective jaws on the one hand and the head and member on the other, and means for moving the table and the central head axially to cause said toggle links to operate their respective jaws.

32. A machine for operating upon rims for motor vehicle wheels and similar objects having, in combination, a table, a series of slides mounted for radial movement on the table, means for moving said slides radially toward the center of the table said slides having a circular series of die members thereon operating in such inward movement of the slides to engage and shrink the work to a predetermined size, a cutting tool mounted on one of said slides, and means operating upon completion of the shrinking operation to move said cutting tool into engagement with the work.

33. In a machine of the character described, the combination of a table, a slide movable upon said table, a pair of abutment members on opposite sides of said slide, said table and abutment members being mounted for relative axial movement, a toggle interposed between said slide and one of said members, a die member movable with the slide, a second die member mounted on the slide, and a second toggle interposed between said second die member and the other one of said members, the arrangement being such that in the relative axial movement between the table and members the first mentioned die member is moved with the slide into engagement with the work and thereupon the second die member is moved upon the slide into engagement with the work.

34. A machine of the character described comprising in combination, a table, a circular series of jaws mounted for radial sliding movement on the table, an abutment member surrounding said circular series of jaws, and toggle links interposed between the jaws and said member, said table and member being mounted for relative movement, another jaw mounted on the table so as to be adapted to receive between it and

the circular series of jaws a piece of work, a head adjacent the second jaw, a toggle link interposed between the head and the second jaw, and means for effecting relative movement first between the table and said member to move the circular series of jaws into engagement with the work, then to effect relative movement between the head and the table whereby to move the second jaw into engagement with the work.

35. A machine of the character described comprising, in combination, a table, a circular series of jaws mounted for radial sliding movement on the table, an abutment member surrounding said circular series of jaws, said table and member being mounted for relative movement, another jaw mounted on the table so as to be adapted to receive between it and the circular series of jaws a piece of work, a head adjacent the second jaw, means for effecting relative movement first between the table and said member, and means operating in such relative movement first to move the circular series of jaws into engagement with the work and then to effect relative movement between the head and the table whereby to move the second jaw into engagement with the work.

36. In a rim sizing and punching machine, the combination with means for sizing a rim, including a radially movable block engageable with the rim, of a punch engageable with the rim and movable independently of and guided by said block, and means for actuating said rim sizing means and punch in timed relation to successively size and punch the rim.

In testimony whereof I affix my signature.
WILLIAM N. BOOTH.
